The ornamental design for a hat, as shown and described.

DESCRIPTION

FIG. 1 is a perspective view of a first embodiment of a hat with the text of NEW YORK, showing our new design;

FIG. 2 is a front elevational view corresponding to FIG. 1;

FIG. 3 is a rear elevational view corresponding to FIG. 1;

FIG. 4 is a right side elevational view corresponding to FIG. 1;

FIG. 5 is a left side elevational view corresponding to FIG. 1; FIG. 6 is a top plan view corresponding to FIG. 1;

FIG. 7 is a bottom plan view corresponding to FIG. 1;

FIG. 8 is a perspective view of a second embodiment of a hat with the text of MIAMI, showing our new design;

FIG. 9 is a front elevational view corresponding to FIG. 8;

FIG. 10 is a rear elevational view corresponding to FIG. 8;

FIG. 11 is a right side elevational view corresponding to FIG. 8;

FIG. 12 is a left side elevational view corresponding to FIG. 8;

FIG. 13 is a top plan view corresponding to FIG. 8;

FIG. 14 is a bottom plan view corresponding to FIG. 8

FIG. 15 is a perspective view of a third embodiment of a hat with the text of ORLANDO, showing our new design;

FIG. 16 is a front elevational view corresponding to FIG. 15;

FIG. 17 is a rear elevational view corresponding to FIG. 15;

FIG. 18 is a right side elevational view corresponding to FIG. 15;

FIG. 19 is a left side elevational view corresponding to FIG. 15;
FIG. 20 is a top plan view corresponding to FIG. 15;
FIG. 21 is a bottom plan view corresponding to FIG. 15
FIG. 22 is a perspective view of a fourth embodiment of a hat with the text of FLORIDA, showing our new design;
FIG. 23 is a front elevational view corresponding to FIG. 22;
FIG. 24 is a rear elevational view corresponding to FIG. 22;
FIG. 25 is a right side elevational view corresponding to FIG. 22;
FIG. 26 is a left side elevational view corresponding to FIG. 22;
FIG. 27 is a top plan view corresponding to FIG. 22;
FIG. 28 is a bottom plan view corresponding to FIG. 22
FIG. 29 is a perspective view of a fifth embodiment of a hat with the text of PUERTO RICO, showing our new design;
FIG. 30 is a front elevational view corresponding to FIG. 29;
FIG. 31 is a rear elevational view corresponding to FIG. 29;
FIG. 32 is a right side elevational view corresponding to FIG. 29;
FIG. 33 is a left side elevational view corresponding to FIG. 29;
FIG. 34 is a top plan view corresponding to FIG. 29;
FIG. 35 is a bottom plan view corresponding to FIG. 29
FIG. 36 is a perspective view of a sixth embodiment of a hat with the text of MYRTLE BEACH, showing our new design;
FIG. 37 is a front elevational view corresponding to FIG. 36;
FIG. 38 is a rear elevational view corresponding to FIG. 36;
FIG. 39 is a right side elevational view corresponding to FIG. 36;
FIG. 40 is a left side elevational view corresponding to FIG. 36;
FIG. 41 is a top plan view corresponding to FIG. 36;
FIG. 42 is a bottom plan view corresponding to FIG. 36
FIG. 43 is a perspective view of a seventh embodiment of a hat with the text of LAS VEGAS, showing our new design;
FIG. 44 is a front elevational view corresponding to FIG. 43;
FIG. 45 is a rear elevational view corresponding to FIG. 43;
FIG. 46 is a right side elevational view corresponding to FIG. 43;
FIG. 47 is a left side elevational view corresponding to FIG. 43;
FIG. 48 is a top plan view corresponding to FIG. 43;
FIG. 49 is a bottom plan view corresponding to FIG. 43
FIG. 50 is a perspective view of a eighth embodiment of a hat with the text of LOS ANGELES, showing our new design;
FIG. 51 is a front elevational view corresponding to FIG. 50;
FIG. 52 is a rear elevational view corresponding to FIG. 50;
FIG. 53 is a right side elevational view corresponding to FIG. 50;
FIG. 54 is a left side elevational view corresponding to FIG. 50;
FIG. 55 is a top plan view corresponding to FIG. 50;
FIG. 56 is a bottom plan view corresponding to FIG. 50
FIG. 57 is a perspective view of a ninth embodiment of a hat with the text of SAN FRANCISCO, showing our new design;
FIG. 58 is a front elevational view corresponding to FIG. 57;
FIG. 59 is a rear elevational view corresponding to FIG. 57;
FIG. 60 is a right side elevational view corresponding to FIG. 57;
FIG. 61 is a left side elevational view corresponding to FIG. 57;
FIG. 62 is a top plan view corresponding to FIG. 57;
FIG. 63 is a bottom plan view corresponding to FIG. 57

FIG. 64 is a perspective view of a tenth embodiment of a hat with the text of CALIFORNIA, showing our new design;
FIG. 65 is a front elevational view corresponding to FIG. 64;
FIG. 66 is a rear elevational view corresponding to FIG. 64;
FIG. 67 is a right side elevational view corresponding to FIG. 64;
FIG. 68 is a left side elevational view corresponding to FIG. 64;
FIG. 69 is a top plan view corresponding to FIG. 64;
FIG. 70 is a bottom plan view corresponding to FIG. 64
FIG. 71 is a perspective view of an eleventh embodiment of a hat with the text of SAN DIEGO, showing our new design;
FIG. 72 is a front elevational view corresponding to FIG. 71;
FIG. 73 is a rear elevational view corresponding to FIG. 71;
FIG. 74 is a right side elevational view corresponding to FIG. 71;
FIG. 75 is a left side elevational view corresponding to FIG. 71;
FIG. 76 is a top plan view corresponding to FIG. 71;
FIG. 77 is a bottom plan view corresponding to FIG. 71
FIG. 78 is a perspective view of a twelfth embodiment of a hat with the text of BOSTON, showing our new design;
FIG. 79 is a front elevational view corresponding to FIG. 78;
FIG. 80 is a rear elevational view corresponding to FIG. 78;
FIG. 81 is a right side elevational view corresponding to FIG. 78;
FIG. 82 is a left side elevational view corresponding to FIG. 78;
FIG. 83 is a top plan view corresponding to FIG. 78;
FIG. 84 is a bottom plan view corresponding to FIG. 78
FIG. 85 is a perspective view of a thirteenth embodiment of a hat with the text of NEW ORLEANS, showing our new design;
FIG. 86 is a front elevational view corresponding to FIG. 85;
FIG. 87 is a rear elevational view corresponding to FIG. 85;
FIG. 88 is a right side elevational view corresponding to FIG. 85;
FIG. 89 is a left side elevational view corresponding to FIG. 85;
FIG. 90 is a top plan view corresponding to FIG. 85;
FIG. 91 is a bottom plan view corresponding to FIG. 85
FIG. 92 is a perspective view of a fourteenth embodiment of a hat with the text of TEXAS, showing our new design;
FIG. 93 is a front elevational view corresponding to FIG. 92;
FIG. 94 is a rear elevational view corresponding to FIG. 92;
FIG. 95 is a right side elevational view corresponding to FIG. 92;
FIG. 96 is a left side elevational view corresponding to FIG. 92;
FIG. 97 is a top plan view corresponding to FIG. 92;
FIG. 98 is a bottom plan view corresponding to FIG. 92
FIG. 99 is a perspective view of a fifteenth embodiment of a hat with the text of WASHINGTON, showing our new design;
FIG. 100 is a front elevational view corresponding to FIG. 99;
FIG. 101 is a rear elevational view corresponding to FIG. 99;
FIG. 102 is a right side elevational view corresponding to FIG. 99;
FIG. 103 is a left side elevational view corresponding to FIG. 99;
FIG. 104 is a top plan view corresponding to FIG. 99;
FIG. 105 is a bottom plan view corresponding to FIG. 99
FIG. 106 is a perspective view of a sixteenth embodiment of a hat with the text of CHICAGO, showing our new design;
FIG. 107 is a front elevational view corresponding to FIG. 106;

FIG. 108 is a rear elevational view corresponding to FIG. 106; FIG. 109 is a right side elevational view corresponding to FIG. 106; FIG. 110 is a left side elevational view corresponding to FIG. 106; FIG. 111 is a top plan view corresponding to FIG. 106; FIG. 112 is a bottom plan view corresponding to FIG. 106 FIG. 113 is a perspective view of a seventeenth embodiment of a hat with the text of HAWAII, showing our new design; FIG. 114 is a front elevational view corresponding to FIG. 113; FIG. 115 is a rear elevational view corresponding to FIG. 113; FIG. 116 is a right side elevational view corresponding to FIG. 113; FIG. 117 is a left side elevational view corresponding to FIG. 113; FIG. 118 is a top plan view corresponding to FIG. 113; FIG. 119 is a bottom plan view corresponding to FIG. 113 FIG. 120 is a perspective view of an eighteenth embodiment of a hat with the text of ATLANTA, showing our new design; FIG. 121 is a front elevational view corresponding to FIG. 120; FIG. 122 is a rear elevational view corresponding to FIG. 120; FIG. 123 is a right side elevational view corresponding to FIG. 120; FIG. 124 is a left side elevational view corresponding to FIG. 120; FIG. 125 is a top plan view corresponding to FIG. 120; FIG. 126 is a bottom plan view corresponding to FIG. 120 FIG. 127 is a perspective view of a nineteenth embodiment of a hat with the text of DALLAS, showing our new design; FIG. 128 is a front elevational view corresponding to FIG. 127; FIG. 129 is a rear elevational view corresponding to FIG. 127; FIG. 130 is a right side elevational view corresponding to FIG. 127; FIG. 131 is a left side elevational view corresponding to FIG. 127; FIG. 132 is a top plan view corresponding to FIG. 127; FIG. 133 is a bottom plan view corresponding to FIG. 127 FIG. 134 is a perspective view of a twentieth embodiment of a hat with the text of NASHVILLE, showing our new design; FIG. 135 is a front elevational view corresponding to FIG. 134; FIG. 136 is a rear elevational view corresponding to FIG. 134; FIG. 137 is a right side elevational view corresponding to FIG. 134; FIG. 138 is a left side elevational view corresponding to FIG. 134; FIG. 139 is a top plan view corresponding to FIG. 134; FIG. 140 is a bottom plan view corresponding to FIG. 134 FIG. 141 is a perspective view of a twenty-first embodiment of a hat with the text of PHILADELPHIA, showing our new design; FIG. 142 is a front elevational view corresponding to FIG. 141; FIG. 143 is a rear elevational view corresponding to FIG. 141; FIG. 144 is a right side elevational view corresponding to FIG. 141; FIG. 145 is a left side elevational view corresponding to FIG. 141; FIG. 146 is a top plan view corresponding to FIG. 141; FIG. 147 is a bottom plan view corresponding to FIG. 141

FIG. 148 is a perspective view of a twenty-second embodiment of a hat with the text of MARYLAND, showing our new design; FIG. 149 is a front elevational view corresponding to FIG. 148; FIG. 150 is a rear elevational view corresponding to FIG. 148; FIG. 151 is a right side elevational view corresponding to FIG. 148; FIG. 152 is a left side elevational view corresponding to FIG. 148; FIG. 153 is a top plan view corresponding to FIG. 148; FIG. 154 is a bottom plan view corresponding to FIG. 148 FIG. 155 is a perspective view of a twenty-third embodiment of a hat with the text of MINNEAPOLIS, showing our new design; FIG. 156 is a front elevational view corresponding to FIG. 155; FIG. 157 is a rear elevational view corresponding to FIG. 155; FIG. 158 is a right side elevational view corresponding to FIG. 155; FIG. 159 is a left side elevational view corresponding to FIG. 155; FIG. 160 is a top plan view corresponding to FIG. 155; FIG. 161 is a bottom plan view corresponding to FIG. 155 FIG. 162 is a perspective view of a twenty-fourth embodiment of a hat with the text of MINNESOTA, showing our new design; FIG. 163 is a front elevational view corresponding to FIG. 162; FIG. 164 is a rear elevational view corresponding to FIG. 162; FIG. 165 is a right side elevational view corresponding to FIG. 162; FIG. 166 is a left side elevational view corresponding to FIG. 162; FIG. 167 is a top plan view corresponding to FIG. 162; FIG. 168 is a bottom plan view corresponding to FIG. 162 FIG. 169 is a perspective view of a twenty-fifth embodiment of a hat with the text of KEY WEST, showing our new design; FIG. 170 is a front elevational view corresponding to FIG. 169; FIG. 171 is a rear elevational view corresponding to FIG. 169; FIG. 172 is a right side elevational view corresponding to FIG. 169; FIG. 173 is a left side elevational view corresponding to FIG. 169; FIG. 174 is a top plan view corresponding to FIG. 169; FIG. 175 is a bottom plan view corresponding to FIG. 169 FIG. 176 is a perspective view of a twenty-sixth embodiment of a hat with the text of ALASKA, showing our new design; FIG. 177 is a front elevational view corresponding to FIG. 176; FIG. 178 is a rear elevational view corresponding to FIG. 176; FIG. 179 is a right side elevational view corresponding to FIG. 176; FIG. 180 is a left side elevational view corresponding to FIG. 176; FIG. 181 is a top plan view corresponding to FIG. 176; FIG. 182 is a bottom plan view corresponding to FIG. 176 FIG. 183 is a perspective view of a twenty-seventh embodiment of a hat with the text of NEW JERSEY, showing our new design; FIG. 184 is a front elevational view corresponding to FIG. 183; FIG. 185 is a rear elevational view corresponding to FIG. 183;

FIG. 186 is a right side elevational view corresponding to FIG. 183;
FIG. 187 is a left side elevational view corresponding to FIG. 183;
FIG. 188 is a top plan view corresponding to FIG. 183;
FIG. 189 is a bottom plan view corresponding to FIG. 183
FIG. 190 is a perspective view of a twenty-eighth embodiment of a hat with the text of NORTH CAROLINA, showing our new design;
FIG. 191 is a front elevational view corresponding to FIG. 190;
FIG. 192 is a rear elevational view corresponding to FIG. 190;
FIG. 193 is a right side elevational view corresponding to FIG. 190;
FIG. 194 is a left side elevational view corresponding to FIG. 190;
FIG. 195 is a top plan view corresponding to FIG. 190;
FIG. 196 is a bottom plan view corresponding to FIG. 190
FIG. 197 is a perspective view of a twenty-ninth embodiment of a hat with the text of TENNESSE, showing our new design;
FIG. 198 is a front elevational view corresponding to FIG. 197;
FIG. 199 is a rear elevational view corresponding to FIG. 197;
FIG. 200 is a right side elevational view corresponding to FIG. 197;
FIG. 201 is a left side elevational view corresponding to FIG. 197;
FIG. 202 is a top plan view corresponding to FIG. 197;
FIG. 203 is a bottom plan view corresponding to FIG. 197
FIG. 204 is a perspective view of a thirtieth embodiment of a hat with the text of ATLANTIC CITY, showing our new design;
FIG. 205 is a front elevational view corresponding to FIG. 204;
FIG. 206 is a rear elevational view corresponding to FIG. 204;
FIG. 207 is a right side elevational view corresponding to FIG. 204;
FIG. 208 is a left side elevational view corresponding to FIG. 204;
FIG. 209 is a top plan view corresponding to FIG. 204;
FIG. 210 is a bottom plan view corresponding to FIG. 204
FIG. 211 is a perspective view of a thirty-first embodiment of a hat with the text of KANSAS CITY, showing our new design;
FIG. 212 is a front elevational view corresponding to FIG. 211;
FIG. 213 is a rear elevational view corresponding to FIG. 211;
FIG. 214 is a right side elevational view corresponding to FIG. 211;
FIG. 215 is a left side elevational view corresponding to FIG. 211;
FIG. 216 is a top plan view corresponding to FIG. 211;
FIG. 217 is a bottom plan view corresponding to FIG. 211
FIG. 218 is a perspective view of a thirty-second embodiment of a hat with the text of KENTUCKY, showing our new design;
FIG. 219 is a front elevational view corresponding to FIG. 218;
FIG. 220 is a rear elevational view corresponding to FIG. 218;
FIG. 221 is a right side elevational view corresponding to FIG. 218;
FIG. 222 is a left side elevational view corresponding to FIG. 218;
FIG. 223 is a top plan view corresponding to FIG. 218;
FIG. 224 is a bottom plan view corresponding to FIG. 218

FIG. 225 is a perspective view of a thirty-third embodiment of a hat with the text of MEMPHIS, showing our new design;
FIG. 226 is a front elevational view corresponding to FIG. 225;
FIG. 227 is a rear elevational view corresponding to FIG. 225;
FIG. 228 is a right side elevational view corresponding to FIG. 225;
FIG. 229 is a left side elevational view corresponding to FIG. 225;
FIG. 230 is a top plan view corresponding to FIG. 225;
FIG. 231 is a bottom plan view corresponding to FIG. 225
FIG. 232 is a perspective view of a thirty-fourth embodiment of a hat with the text of OHIO, showing our new design;
FIG. 233 is a front elevational view corresponding to FIG. 232;
FIG. 234 is a rear elevational view corresponding to FIG. 232;
FIG. 235 is a right side elevational view corresponding to FIG. 232;
FIG. 236 is a left side elevational view corresponding to FIG. 232;
FIG. 237 is a top plan view corresponding to FIG. 232;
FIG. 238 is a bottom plan view corresponding to FIG. 232
FIG. 239 is a perspective view of a thirty-fifth embodiment of a hat with the text of ARIZONA, showing our new design;
FIG. 240 is a front elevational view corresponding to FIG. 239;
FIG. 241 is a rear elevational view corresponding to FIG. 239;
FIG. 242 is a right side elevational view corresponding to FIG. 239;
FIG. 243 is a left side elevational view corresponding to FIG. 239;
FIG. 244 is a top plan view corresponding to FIG. 239;
FIG. 245 is a bottom plan view corresponding to FIG. 239
FIG. 246 is a perspective view of a thirty-sixth embodiment of a hat with the text of PENNSYLVANIA, showing our new design;
FIG. 247 is a front elevational view corresponding to FIG. 246;
FIG. 248 is a rear elevational view corresponding to FIG. 246;
FIG. 249 is a right side elevational view corresponding to FIG. 246;
FIG. 250 is a left side elevational view corresponding to FIG. 246;
FIG. 251 is a top plan view corresponding to FIG. 246;
FIG. 252 is a bottom plan view corresponding to FIG. 246
FIG. 253 is a perspective view of a thirty-seventh embodiment of a hat with the text of PITTSBURGH, showing our new design;
FIG. 254 is a front elevational view corresponding to FIG. 253;
FIG. 255 is a rear elevational view corresponding to FIG. 253;
FIG. 256 is a right side elevational view corresponding to FIG. 253;
FIG. 257 is a left side elevational view corresponding to FIG. 253;
FIG. 258 is a top plan view corresponding to FIG. 253;
FIG. 259 is a bottom plan view corresponding to FIG. 253
FIG. 260 is a perspective view of a thirty-eighth embodiment of a hat with the text FORT LAUDERDALE, showing our new design;
FIG. 261 is a front elevational view corresponding to FIG. 260;
FIG. 262 is a rear elevational view corresponding to FIG. 260;
FIG. 263 is a right side elevational view corresponding to FIG. 260;

FIG. 264 is a left side elevational view corresponding to FIG. 260;

FIG. 265 is a top plan view corresponding to FIG. 260; and,

FIG. 266 is a bottom plan view corresponding to FIG. 260.

The broken lines shown in the perspective and elevation views of the design represent portions of the hat that form no part of the claimed design. The broken lines encircling the bottom interior of the hat shown in FIGS. 7, 14, 21, 28, 35, 42,

49, 56, 63, 70, 77, 84, 91, 98, 105, 112, 119, 126, 133, 140, 147, 154, 161, 168, 175, 182, 189, 196, 203, 210, 217, 224, 231, 238, 245, 252, 259 and 266 define the boundaries of a portion of the hat that is not claimed. The broken line boundaries form no part of the claimed design.
